UNITED STATES PATENT OFFICE.

CHARLES C. WITMER AND BECKWITH HAVENS, OF HAMMONDSPORT, NEW YORK,
ASSIGNORS TO "AIRSHIPS INCORPORATED," OF HAMMONDSPORT, NEW YORK,
A CORPORATION OF NEW YORK.

PNEUMATIC LIFE RAFT.

Application filed November 17, 1921. Serial No. 515,931.

To all whom it may concern:

Be it known that we, CHARLES C. WITMER and BECKWITH HAVENS, citizens of the United States, residing at Hammondsport, 5 in the county of Steuben and State of New York, have invented certain new and useful Improvements in Pneumatic Life Rafts, of which the following is a specification.

This invention relates to inflatable pneumatic floatable bodies, and the primary object of the invention is to provide a novel pneumatic device, which can be effectively used either as a life raft on ocean going steamers or the like, or as a pleasure device 15 at watering resorts.

Another object of the invention is the provision of an annular pneumatic body formed of balloon cloth or some other similar strong fluid proof material, having a novel circular 20 flexible platform associated therewith forming a jumping platform and the like when the body is used in connection with water sports.

A further object of the invention is the provision of a raft having light weight and 25 formed of cushioned material which can be carried on boats and which can be used as a buoy to be thrown overboard when a person or persons is precipitated in the water, the 30 device being formed of soft material for preventing the person or persons being injured by coming in contact with the buoy when the same is thrown overboard from the boat.

35 A further object of the invention is to provide a novel pneumatic raft of annular construction capable of supporting a number of persons, and which has the periphery thereof provided with rope handles or a loop line 40 for facilitating the grasping of the buoy by persons in the water.

45 A further object of the invention is the provision of a novel means for forming the annular body of the raft, the annular body consisting of a plurality of arcuate sections each forming an independent air compartment, so that if one compartment or section is perforated, the body will still be capable of sustaining a number of persons.

50 Further objects of the invention are the provision of a novel means for connecting the terminals of the arcuate sections together, a novel means for connecting the bulk heads for dividing the sections from

one another, and a novel means for holding 65 the partitions in the body for preventing the washing back and forth of the air therein, when the load on the raft is shifted, the bulk heads and the partition forming reinforcing members for the sections.

60 A still further object of the invention is the provision of means for connecting the circular platform with the annular inflatable pneumatic body, said means including an annular grommet strip to which the platform 65 can be laced, the strip also forming means for strengthening the body.

A still further object of the invention is to provide a pneumatic raft of the above character, which will be durable and efficient 70 in use, one that will be simple and easy to manufacture, and one which can be placed upon the market at a reasonable cost.

75 With these and other objects in view, the invention consists in the novel construction, arrangement and formation of parts, as will be hereinafter more specifically described and claimed and illustrated in the accompanying drawings, forming a part of this specification, in which drawings:

80 Figure 1 is a plan view of the improved life raft, showing the same provided with a looped line for sea work.

Figure 2 is a side elevation of the raft.

Figure 3 is a fragmentary inner elevation 85 of the improved raft.

Figure 4 is a fragmentary longitudinal section on an enlarged scale, taken on the line 4-4 of Figure 1.

Figure 5 is an enlarged fragmentary horizontal section through the raft showing the method of securing the bulk heads therein, and the means of connecting the grommet strip to the inner periphery of the body.

Figure 6 is an enlarged fragmentary 95 transverse section taken on the line 6-6 of Figure 5.

Figure 7 is an enlarged fragmentary longitudinal section taken on the line 7-7 of Figure 1 showing the means of connecting 100 the partition plates in position.

Figure 8 is a transverse section through the inflatable body with the grommet strip removed.

Figure 9 is an elevation of the attaching 105 patch and flexible supporting ropes carried thereby.

Figure 10 is a section taken on the line

10—10 of Figure 9, showing the means of securing the attaching patch and the terminals of the flexible supporting rope in position.

5 Figure 11 is a plan view of the improved life raft showing the same provided with rope handles, instead of the annular looped hand line.

Referring to the drawings in detail, where-
10 in similar reference characters designate corresponding parts throughout the several views, the letter A indicates the annular pneumatic body; B, the grommet strip carried thereby; and C, the platform which is
15 adapted to be laced to the grommet strip.

The annular pneumatic inflatable body A comprises a plurality of arcuate sections 10, 11, 12 and 13, which have their terminals connected together in a novel manner. While
20 I have only shown four of these arcuate sections, it is obvious that more or less of these sections can be used according to the size of the annular body. Each section includes an upper semi-circular wall 15 and a lower
25 semi-circular wall 16. The meeting longitudinal edges of these walls are overlapped as at 17 and cemented together. The outer periphery of the body A has an annular strengthening tape or band 18 extending entirely around the same, which serves as
30 means for sealing the joint or seam, and the inner periphery of the body has cemented thereto an inner reinforcing band 19, which extends entirely around the same and seals the joint at its inner periphery. The inner surface of the body at the points of connection of the upper and lower walls 15 and 16 are also sealed by inner reinforcing strips or tapes 20 and 21, which extend annularly
35 around the inner surface of the body. This forms a strong and durable construction and not only serves as means for sealing the joint but also strengthens the entire structure. The terminals of the sections 10, 11,
40 12 and 13, have their inner ends overlapped or telescoped as at 25, as clearly shown in Figure 4 of the drawings. Extending transversely around the joint 25 are annularly extending reinforcing strips or tapes 26,
45 which serve as means for sealing the joints. An inner reinforcing tape 27 is also used, to strengthen the joint. These tapes and the meeting terminals of the sections are all cemented together as clearly shown in the
50 drawings.

A bulk head 30 is positioned at each joint so as to form each section into an independent air compartment, and each of these sections is provided with suitable valves 28,
55 whereby the same may be independently inflated. The bulk heads 30 are also formed of balloon cloth and consists of the disc-shaped divisional wall 31 and the right angularly extending annular attaching flanges
60 32, which are cemented or otherwise secured

to the reinforcing inner tape 27 as at 33. A shoe or attaching member 34 is also utilized for securing the bulk head 30 in position and can be formed of balloon cloth, if so desired, and consists of a pair of angular related walls 35 and 36, which are secured respectively to the disc shaped body portion 31 of the bulk head 30 and to the inner reinforcing annular tape 27. It thus can be seen that the bulk heads 30 and the annular transversely extending tapes 26 and 27 add rigidity to the pneumatic body and strength thereto.

Disposed intermediate the ends of each section and directly between the bulk heads 30 is disc shaped partition plates 40. These partition plates 40 are provided at their axis with openings 41 and these plates or partitions simply serve as means for preventing the washing back and forth of the air within the sections. The partitions are secured in place similar to the bulk heads and it can be seen by referring to Figure 5 of the drawings that the periphery of the partitions 40 are provided with outwardly extending attaching flanges 42, which can be secured to annular reinforcing tapes 43, which can be cemented to the inner surface of the sections. A shoe 44 is further utilized to hold each partition in place and these shoes consist of angular related walls 45 and 46, which are cemented respectively to the partition plates and to the reinforcing tapes 43. It also is to be noted that the attaching flanges 42 are also secured to the reinforcing tapes.

To the inner periphery of the body A is cemented or otherwise secured the grommet strip B, to which is adapted to be laced the flexible platform C. The grommet strip B also forms an additional means for strengthening the body A and is of annular formation and can be made of strong canvas. As shown, this strip is folded intermediate its ends to provide an outwardly extending supporting flange 50 which has interposed therein a stiffening ring 51, which can also be formed of canvas if so desired. Extending outwardly from the opposite sides of the supporting flange 50, are the attaching flanges 52 and 53, which are preferably cemented to the inner periphery of the body A as heretofore stated. These attaching flanges 52 and 53 extend up the sides of the body A for a considerable distance as clearly shown in Figure 3 of the drawings.

The platform C can be made of canvas or other flexible heavy material and is of a disc shape and has secured thereto adjacent to its periphery reinforcing eyelets 54. The supporting flange 50 also has secured thereto reinforcing eyelets 55 and a suitable lacing 56 can be utilized for connecting the platform to the grommet band and this lacing is threaded through the eyelets 54 and 55 as

clearly shown in Figures 1, 5 and 11 of the drawings.

The outer periphery of the body A at the circumferential center thereof may have secured thereto a hand line 60, as clearly shown in Figure 1 of the drawings, or rope handles 70 as shown in Figure 11 of the drawings for beach work or for water sports. The hand line 60 is formed of rope and threaded through suitable eyes 61, which are also preferably formed of rope. The eyes 61 are connected to the periphery of the body A in a novel manner, and it can be seen that the rope utilized for the eyes is lopped to form the eye and then served as at 62. The ends of the rope below the served portions are frayed outwardly as at 63. The served part of the eye portion is passed through an opening in an enlarged patch 65, which is cemented or otherwise secured to the outer face of the annular body and the outer reinforcing band 18. The patch 65 completely houses the frayed end of the rope and forms a strong and durable means for securing the eye in position. The eyes 61 are arranged in circumferential alignment and receive the hand line 60.

When the rope handles 70 are used, the same are secured in position similar to the eyes 61, that is the terminals of the rope are frayed out and passed beneath patches 71 and securely cemented to the inner surface of the patches and to the outer surface of the body A and the annular reinforcing band 18. The patches are of course, cemented in position.

From the foregoing, it can be seen that a pneumatic life raft has been provided, which can be used both as a life raft or a buoy or at watering places for watering sports.

If desired, the raft can be carried in a deflated condition and inflated in time of emergencies when used on boats.

Changes in details may be made without departing from the spirit or scope of this invention; but,

We claim:

1. A pneumatic raft comprising an annular flexible body formed from balloon cloth, a plurality of partitions dividing the body into a plurality of independent air compartments, and perforated partitions arranged in each compartment, whereby the washing back and forth of fluid in said compartments during change of load thereon is prevented.

2. A pneumatic raft comprising an annular flexible body, means for inflating the body, inner and outer flexible reinforcing strips carried by the inner and outer peripheries of said body, and transversely extending reinforcing strips disposed about said body and said first mentioned strip at predetermined points.

3. A pneumatic raft comprising an annular body formed of flexible material, cir-

cumferentially extending reinforcing strips secured to the inner and outer peripheries of said body, transversely extending annular reinforcing strips disposed about said body at predetermined points, and a grommet band having a plurality of eyelets therein secured to the inner periphery of the body and extending above and below the inner circumferentially extending reinforcing strip, and an adjustable platform secured to said grommet band.

4. In a pneumatic raft, a flexible inflatable body, a grommet strip formed of flexible material folded intermediate its ends to provide an outwardly extending supporting flange, and outwardly attaching flanges, the supporting flange having a plurality of eyelets therein, a disc shaped platform having a plurality of eyelets formed adjacent to one periphery thereof, and a lacing extending through said eyelets to secure the platform to said grommet strip.

5. A pneumatic raft comprising an annular body including a plurality of flexible arcuate sections having the meeting terminals disposed in overlapped relation and secured together, circumferentially extending flexible reinforcing bands secured to the inner and outer peripheries of said body and to the inner surface of the body at diametrically opposite points, transversely extending flexible reinforcing bands secured about the body and said circumferentially extending reinforcing bands at the points of connections of said sections, and means for inflating the body.

6. A pneumatic raft comprising an annular body including a plurality of flexible arcuate sections having their meeting terminals disposed in overlapped relation and secured together, circumferentially extending flexible reinforcing bands secured to the inner surface of the body diametrically opposite points, transversely extending flexible reinforcing bands disposed about the body at the points of connections of said sections, means for inflating the body, and bulk heads disposed in said body at the points of connection of said arcuate sections for forming a plurality of independent inflatable bodies.

7. In a pneumatic raft, an annular body formed of flexible material comprising a plurality of arcuate sections having their meeting terminals disposed in overlapping relation and secured together, circumferentially extending reinforcing bands secured to the inner and outer peripheries of the body, and inner circumferentially extending bands secured to the inner surface of the body at diametrically opposite points, transversely extending reinforcing bands secured to the inner and outer surface of the body at the points of connections of the arcuate sections, bulk heads disposed in said body at the points of connection of said sections.

and including a disc shaped wall, and an arcuately extending annular attaching flange secured to the inner surface of the body at the points of connection of the sections, and a reinforcing shoe for each bulk head including angularly related annular flanges secured respectively to the bulk head and to the inner surface of the body.

8. In a pneumatic raft, an annular body 10 formed of flexible material comprising a plurality of arcuate sections having their meeting terminals disposed in overlapping relation and secured together, circumferentially extending reinforcing bands secured 15 to the inner and outer peripheries of the body, and inner circumferentially extending bands secured to the inner surface of the body at diametrically opposite points, transversely extending reinforcing bands 20 secured to the inner and outer surface of the body at the points of connection of the arcuate sections, bulk heads disposed in said body at the points of connection of said sections and including a 25 disc shaped wall and arcuately extending annular attaching flanges secured to the inner surface of the body at the points of connection of the sections, and a reinforcing shoe for each bulk head including angularly 30 related annular flanges secured respectively to the bulk head and to the inner surface of the body, and a reinforcing annular circumferentially extending strip interposed between the bulk head and attaching shoe and 35 the inner surface of the body.

9. In a pneumatic raft, an annular flexible body including a plurality of arcuate sections having their terminals overlapped,

circumferentially extending reinforcing bands secured respectively to the inner and 40 the outer periphery of the body, transversely extending reinforcing strips disposed about said body at the points of connections of said sections, flexible rope supporting members secured to the outer surface of the body 45 and reinforcing patches for said flexible supporting members secured to the outer surface of the body at the points of connections of said sections.

10. In a pneumatic raft, a flexible inflatable body, flexible supporting members having the terminals thereof frayed and spread out in contact with the outer surface of the body, a reinforcing patch having an opening therein for receiving the flexible supporting member, the patch engaging the frayed end of the flexible member to secure the same in position on the body and for reinforcing the body.

11. In a pneumatic raft including an annular body formed of arcuate sections, bulk heads disposed in the body at the points of connections of said sections providing a plurality of independent compartments, means for inflating the compartments, and partitions disposed in each one of the sections having an axial opening therein including an outwardly extending attaching flange for engaging the inner surface of the sections, and an attaching shoe including annular attaching flanges secured respectively to the partition and to the inner surface of the body.

CHARLES C. WITMER.
BECKWITH HAVENS.
